UNITED STATES PATENT OFFICE.

GEORGE E. LEE, OF CLEVELAND, OHIO, ASSIGNOR TO THE GEORGE E. LEE COMPANY, OF CLEVELAND, OHIO, A CORPORATION OF OHIO.

FUEL-REGULATING DEVICE.

1,228,793.

Specification of Letters Patent.

Patented June 5, 1917.

Application filed February 19, 1914. Serial No. 819,676.

To all whom it may concern:

Be it known that I, GEORGE E. LEE, a citizen of the United States, residing at Cleveland, in the county of Cuyahoga and State 5 of Ohio, have invented a certain new and useful Improvement in Fuel-Regulating Devices, of which the following is a full, clear, and exact description.

This invention relates to controlling devices which are more particularly adapted to control the flow of a fluid fuel to a burner.

The device herein described finds particular utility as a regulator for controlling the supply of fuel to a burner, which controls 15 the melting of metal to be supplied to the melting pot of a linotype machine.

Generally speaking, the invention comprises the elements and combinations thereof set forth in the accompanying claims.

Reference should be had to the accompanying drawings forming a part of this specification, in which Figure 1 is a sectional elevation of a controlling device shown in its relation to the melting pot and auxiliary 20 melting cup of a linotype machine. Fig. 2 is a sectional elevation of a modified form of valve for the controlling device; and Fig. 3 is a sectional elevation of still another modification of the valve for the controlling 25 device.

In the drawing, 1 represents a portion of the melting pot of a linotype machine, and at 2 there is indicated a bracket forming a part of the usual construction of a linotype 35 machine, by which the melting pot is supported.

Above the melting pot there is an auxiliary melting cup indicated at 3, and within this cup there stands an ingot 4 of metal. 40 The cup is provided with an opening 3^a adjacent the lower portion thereof, by which the metal that may be melted from the ingot 4, will find egress from the cup 3, and drop into the bath of metal within the melting pot 1.

The cup 3 is supported upon a suitable arm 5, which in turn is supported by a bracket 6 carried upon some fixed part 7 of the linotype machine.

Suitably mounted so as to be beneath the melting cup 3 is a burner 8. This burner 50 may be of any desired construction. The pipe for supplying the fuel gas to the burner, is indicated at 9, and there is a pilot pipe 10 which will always remain lighted, the same

being adjacent the burner 8. The regular supply of gas to the burner 8 is supplied through the controlling device which forms the subject matter of this invention.

The controlling device comprises a tubular member 11 which is slightly conical in shape, or in other words, the wall or walls are slanting,—is suitably supported with respect to the melting pot so that the lower end of this tubular member is immersed in 60 the molten metal within the pot 1. At its upper end, the tubular member 11 is connected with a casing 12, having an extending portion 13, and a central partition 14 which divides the extending portion 13. 65

Within the casing 12 and extending into the tubular member 11 is a pipe or conduit 15, which at its upper end is supported preferably by a screw threaded plug 16, that engages with a screw threaded opening in a 70 cap 17, which forms a closure for the upper part of the casing 12. This cap 17 is suitably packed so that no gas may escape. Adjustment of the plug 16 will raise or lower the tube 15 so as to alter its position 75 with respect to the level of fluid metal in the melting pot 1. The tube 15 at its upper end is provided with openings, such as indicated at 18, by which gaseous fuel supplied to the upper part of the casing 12 will be permitted 80 to pass into the interior of the tube 15.

At the lower end of the tube 15, there is mounted a valve structure which comprises a float 19. This float at its lower end is somewhat pointed and by this construction 90 together with the outwardly slanting inner surface of the tubular member 11, it is impossible for the dross which is always present on the surface of the metal of the melting pot, to wedge in between the float 19 and the wall of the tubular member 11, and so prevent operation of the valve at proper times.

A portion of the float 19 is hollow, and receives the lower end of the pipe or tube 15. 100 A transverse bar 20 is carried by the tube 15 and extends adjacent its outer end through openings 19^a in the float 19. These openings 19^a are of sufficient size to permit a slight amount of play for the purpose directly to be mentioned.

The bottom surface of the interior portion of the float 19 is cone-shaped, and resting upon the same is a ball 21. This ball is adapted to coöperate with the lower end of 110

tube 15, and when so coöperating prevents the passage of gaseous fuel through the tube 15. The lower portion of the tube 15 is suitably ground and prepared so that the ball 5 when engaging the same may make a gas tight fit.

As before mentioned, the openings 19^a are of sufficient size to permit slight relative movement between the float 19 and the bar 20, and this movement is just sufficient to permit the ball to seat itself against the lower end of tube 15. It will be apparent that the particular formation of the bottom surface inside of the float 19 will always insure the valve being in proper position to engage with the lower end of tube 15.

Fluid fuel from the pipe 9 is supplied to the upper part of casing 12 by means of a suitable connection 22, and the fuel passing 20 from the lower portion of the casing 12 is conducted by a flexible connection 23 to the burner 8.

The operation of the device is as follows: Gaseous fuel is supplied to the pipe 9 and connection 22 with the upper part of the casing 12. The gas then passes through the opening 18 into the interior of the pipe or tube 15, and when the bell 21 is not seated against pipe 15, the gas may flow from the 25 tube 15 through the float 19, and to the lower part of the casing 12, thence through the connection 23 to the burner 8.

Under such conditions, the heat from the burner 8 will melt the ingot 4 within the cup 3, and permit the metal so melted to drop into the molten pot of metal within the pot 1. The metal thus supplied will raise the level of the metal within the pot 1 and when this level has raised a sufficient distance, the float 19 will be raised and cause the ball 21 to seat against the lower end of pipe 15, thus shutting off the supply of gas, and consequently the ingot 4 will cease to be melted.

45 As before stated, the relationship of tube 15 and float 19 to the metal within the pot 1 may be varied by adjusting the plug 16.

In Fig. 2 there is shown a modified form of float coöperating with the tube 15. As 50 herein shown, the float comprises a body portion 24 which is substantially hollow. The lower outside portion of the float is pointed or rounded in a manner similar to the float 19.

55 At the upper portion of the float 24 there is a plug 25, which may have a screw-threaded engagement with the walls of the float 24, or may be otherwise suitably secured. This plug is provided with openings 60 25^a by which the fuel gas may escape, and is also provided with a sleeve 25^b which extends above and below the body of the plug. This sleeve engages with the pipe 15 to have a sliding fit, so that the float 24 may rise 65 and fall with respect to the pipe 15 and be

guided in its movement by the engagement between the sleeve 25^b and the pipe.

In the lower part of the interior portion of the float 24, there is placed a soft compressible material such as asbestos, the same being indicated at 26. The operation will be apparent, viz. that the float 24 as it rises will cause the pipe 15 to be embedded in the material 26, which being compressed will eventually prevent the passage of fluid gas past the lower end of the pipe 15. To provide an efficient cutoff, the lower end of the pipe 15 is brought to an edge, in order that it may more easily form a gas tight joint with the material 26.

80 In Fig. 3 there is shown still a further modified form.

Coöperating with the lower end of the pipe 15 is a float 27 which is of substantially the same construction as far as the body is concerned, as the float 24. At the upper end of the float, there are two wire arms, indicated at 28 and 29. These arms are provided with loops which encircle the pipe 15 and the loops are spaced apart upon this pipe a sufficient distance to insure accurate guiding of the float 27, as it rises and falls.

The interior of the float is partially filled with mercury, as indicated at 30, and it will be apparent that as the float is caused to rise with respect to the pipe 15, the pipe will have its lower end immersed within the mercury 30 and so seal the end of the pipe 15 against the passage of gas therethrough.

95 It will be clear that various modifications in the details of the constructions herein shown and described may be made without departing from the spirit of the invention.

Having thus described my invention, 100 what I claim is:

1. The combination of a melting pot and an auxiliary melting cup discharging into the same, a burner for heating the auxiliary melting cup, a fuel supply conduit to said burner, said conduit extending into the melting pot and having an opening, a valve controlling said opening, said valve being moved to open and closed position by the metal in said pot, as it rises and falls.

110 2. In combination, a melting pot, an auxiliary melting cup discharging into the same, a burner for heating the latter, a fuel supply conduit to said burner, said conduit extending into the melting pot and having an opening, a float coöperating with said opening and having valvular means adapted to open and close the said opening as the float rises and falls by the change in level of the molten metal.

120 3. The combination with a receptacle adapted to hold melted material, of an auxiliary melting cup adapted to hold material in solid form, a burner for heating the melting cup, a regulating device provided with 130

- two chambers, means for leading fuel from one of said chambers, and means for conducting fuel to the other of said chambers to the burner, a conduit extending from the first 5 mentioned chamber and extending adjacent the surface of the melted material within the receptacle, a float member floating upon the surface of the material within the receptacle, coöperating valvular means carried by the 10 float and said conduit for opening and closing the end of said conduit, as the float member rises and falls by the change in level of the material within the receptacle.
4. The combination with a receptacle 15 adapted to hold melted material, of an auxiliary melting cup adapted to hold said material in solid form, a burner for heating the melting cup, a connection for supplying fuel to said burner, a regulating device inserted 20 in said connection, said regulating device comprising an inlet chamber and an outlet chamber, a fuel conduit extending from the inlet chamber into the outlet chamber and adjacent the surface of the molten material 25 within the said receptacle, a float resting upon the material within said receptacle, said float having a portion which surrounds the lower end of the conduit, coöperating means upon said conduit and float for guiding the float as it moves relative to the conduit, and valvular means associated with the 30 float and conduit for causing the end of said conduit to be opened and closed by the rise and fall of the float, due to changes in level 35 of the melted material within the receptacle.
5. The combination with a receptacle adapted to hold melted material, of an auxiliary melting cup adapted to hold said material in solid form, a burner for heating the 40 melting cup, a regulating device comprising a body portion formed with an inlet chamber and an exit chamber, means for conducting fuel to said inlet chamber, and means for conducting the fuel from the outlet 45 chamber to the burner, said body portion at one end extending below the level of the melted material within the receptacle, the walls of this portion of the body slanting outwardly, a conduit connecting the inlet 50 chamber with the outlet chamber, a float member floating on the surface of the melted material, said float member having the lower outward body portion tapered, and valvular means coöperating with the float and conduit 55 for opening and closing the end of said conduit as the float rises and falls by the change in level of the melted material.
6. In combination, a melting pot, an aux- 60
- iliary melting cup discharging into the same, a burner for heating the latter, a fuel supply conduit to said burner, said conduit extending into the melting pot and having an opening, a float, a ball valve carried by the float and adapted to coöperate with the opening in the conduit to open and close said 65 opening as the float falls and rises by the change in level of the molten metal.
7. In combination, a melting pot, an auxiliary melting cup discharging into the same, a burner for heating the latter, a fuel supply 70 conduit to said burner, said conduit extending into the melting pot and having an opening, a float having an interior opening which telescopes the lower part of the conduit, a ball valve within the opening in the 75 float, said ball valve being adapted to coöperate with the opening in the conduit to close and open the same as the float rises and falls by the changes in level of the molten metal.
8. The combination with a receptacle 80 adapted to hold melted material, of an auxiliary melting cup adapted to hold material in solid form, a burner for heating the said melting cup, a regulating device provided with two chambers, means for conducting 85 fuel to one of said chambers, means for conducting fuel from one of the chambers to the other, means for conducting fuel from the other of said chambers to the burner, valvular mechanism governing the passage 90 of fuel between the said chambers said valvular mechanism being directly engaged by the melted material in the aforesaid receptacle and operated by the rise and fall of the molten material within said receptacle. 95
9. The combination with a receptacle adapted to hold melted material, of an auxiliary melting cup adapted to hold material in solid form, a burner for heating the melting cup, a regulating device provided with 100 an inlet chamber and an outlet chamber, the outlet chamber being sealed by the melted material in the receptacle, means for conducting fuel to the inlet chamber, means for conducting fuel from the outlet chamber, valvular mechanism governing the passage 105 of fuel between the chambers said valve being operated by the rise and fall of molten material within said receptacle.

In testimony whereof, I hereunto affix my 110 signature in the presence of two witnesses.

GEORGE E. LEE.
